UNITED STATES PATENT OFFICE.

BERT ELIAS UNDERWOOD, OF SUMMIT, NEW JERSEY.

DESIGN FOR A PHOTOGRAPHIC CABINET.

SPECIFICATION forming part of Design No. 32,412, dated March 27, 1900.

Application filed March 11, 1899. Serial No. 708,762. Term of patent 14 years.

To all whom it may concern:

Be it known that I, BERT ELIAS UNDERWOOD, a citizen of the United States, residing at Summit, in the county of Union and State 5 of New Jersey, have invented and produced a new and original Design for Photographic Cabinets, of which the following is a specification.

This is a design for cabinets or cases and 10 relates to the shape and configuration thereof.

The new design is shown in the accompanying drawing, in which the figure is a perspective view of a photographic cabinet embodying the new design.

15 Referring to the drawing, A represents one part, B another part, and C another part, of the cabinet provided with the new design.

According to the new design the cabinet is 20 of oblong rectangular shape in its general formation, having smooth vertical ends a, smooth flat top b, and an ornamented front c. The front c has at its bottom a narrow bulging band D, extending from end to end of the cabinet and having smooth round end and 25 top edges d. Above the band D is a wider band E of less protrusion and of less length than the band D. The band E rises from the top edge of the band D and has rounded top and end edges. Above the band E are two 30 smooth panels F, having rounded edges f, and above the panels F are two similar panels G,

having edges g. Vertical borders H flank the outer ends of the band E and the panels F and G. Vertical straps I intervene between the adjacent ends of the panels F and G, and horizontal bands J K L are disposed, respectively, immediately above the band E, the panels F, and the panels G. The band K is double the width of the other bands and is traversed by a line h midway between the 35 superposed panels. The end walls have a horizontal bead i crossing their smooth surfaces from front to rear coincident with the line h, and a second bead j at their top extremities coincident with the strap L. The 40 top part b has smooth rounded edges k protruding beyond the strap L in front and over the end walls. Two protuberances l are disposed on the band E, and one such protuberance on each of the panels F and G, and an 45 oblong figure m, having a central rectangular hole n, placed on each of the panels F and G.

What I claim is—

The design for a photographic cabinet substantially as herein described and shown. 50

In witness whereof I have hereunto signed my name in the presence of two subscribing witnesses.

BERT ELIAS UNDERWOOD.
